UNITED STATES PATENT OFFICE.

JOHN NEWBERRY REYNOLDS, OF GREENWICH, CONNECTICUT, ASSIGNOR TO WESTERN ELECTRIC COMPANY, OF NEW YORK, N. Y., A CORPORATION OF ILLINOIS.

MULTIPLE-BRUSH SELECTOR.

1,103,623.

Specification of Letters Patent.

Patented July 14, 1914.

Application filed November 21, 1913. Serial No. 802,280.

To all whom it may concern:

Be it known that I, JOHN NEWBERRY REYNOLDS, a citizen of the United States, residing at Greenwich, in the county of Fairfield 5 and State of Connecticut, have invented a certain new and useful Improvement in Multiple-Brush Selectors, of which the following is a full, clear, concise, and exact description.

10 This invention relates to switching apparatus for use in automatic and semi-automatic telephone systems, and more particularly to switches of the panel type.

One of the objects of this invention is the 15 provision of an improved means for controlling the activity of the brush sets.

Another object resides in the compact and unitary assemblage of the several operating magnets of the switch.

20 A further object resides in the improved means whereby the operation of the down-drive clutch magnet also actuates the release pawl.

A still further object resides in the 25 provision of means whereby an attendant can readily tell on which set of terminals of a section the brushes of the switch rest.

Referring to the drawings Figure 1 is a side elevation of the switch with parts 30 broken away; Fig. 2 is a side elevation of the operating magnet structure with parts broken away; Fig. 3 is a front view of the structure shown in Fig. 2; Fig. 4 shows a portion of the elevating bar and the means 35 for designating the terminals with which the brushes are in engagement; Fig. 5 is a side view of the interrupter mechanism; Fig. 6 is a cross section on the line 6—6 of Fig. 5; Fig. 7 is a plan view of a pair of 40 brush carriers, the brushes of one being shown in an inoperative position, and the brushes of the other being shown in a released or operative position; Fig. 8 is a perspective view of a brush set with parts 45 broken away.

The switch provided by this invention is capable of accurately and rapidly serving a large number of lines, any line being reached through one of a plurality of multiply connected sets of brushes on a common brush shaft. The stationary terminals are arranged in vertical rows in the form of a panel, each row being divided into sections and each section has a set of normally in-

active brushes individual thereto. These 55 rows of terminals may be multiplied horizontally across the panel to be accessible to a many individual switching devices as may be required to handle the greatest number of simultaneous calls.

60 In accordance with this invention, the terminals of the desired line are reached by causing the set of brushes having access to the section of stationary terminals in which the desired line terminates to be released, 65 and then causing said set to traverse the terminals in the section until the terminals of the desired line are reached. All the brushes having access to the sections of a row of terminal sets are secured to a common 70 shaft. The brushes of the several sets are normally held in their retracted position by means of a rotatable cam member, by means of which the brushes are separated laterally, 75 whereby they may pass by the stationary terminals without engagement therewith. A single brush selecting or tripping device is provided for selectively operating said 80 cams to render operative the brushes of any desired set. This brush selecting means 85 comprises a rod extending through the frame, parallel to the brush support or shaft. This rod is provided with a series of inwardly projecting lugs or fingers, one for 90 each brush set, arranged at progressively increasing distances above the normal positions of the operating means for the cams. These fingers normally extend slidably to one side of the line of travel of the several cams, means being provided whereby the trip rod 95 may be momentarily rotated to cause one of said fingers to engage its respective cam in order to release a desired set of brushes. Thus it will be seen that if, during the preliminary upward movement of the brush support at the moment when the operating member of a cam lies in the same vertical plane as one of said trip fingers, the trip rod be momentarily rotated, the appropriate finger will engage the cam of the desired 100 brush set and release the brushes, which, on account of their resiliency, will immediately spring into operative position.

The switch here disclosed is designed to serve 500 lines, the terminals of which are 105 divided into sections of 100 lines each and are duplicated on the opposite sides of the board. It is obvious, however, that the ca-

pacity of the switch may be readily increased by providing a greater number of brushes or by providing more terminals in a section.

In order to avoid needless duplication of the parts, and to more clearly illustrate the parts of the device in which this invention resides, only a portion of a single switching device is shown.

Each individual switch comprises a brush shaft 1, slidably mounted in the guide sleeves 2, carried by the frame members 3. Upon the shaft is secured a plurality of brush carriers comprising the members 4 and 5 clamped about the shaft by means of the screws 6 and 7, or in any desired manner. Insulatively clamped to the members 4 and 5 by means of the screws 7, is a plurality of resilient brushes 8, 9, 10 and 11, each provided at the outer end thereof with a shoe 12 of insulating material. By their resiliency, brushes 8 and 9 are forced toward the brushes 10 and 11. Each of the brushes 8 and 11 is provided with a block of insulating material 13, whereby the brushes of each pair are held in spaced relation as shown in Fig. 7. Thus it will be seen that the brushes 8 and 9 are opposite to brushes 10 and 11, and that when the brush set is released or tripped, brush 8 will engage the terminal 14, brushes 9 and 10 will engage the terminal 15 and brush 11 will engage the terminal 16. Each of the brush arms has an extension ending in a soldering terminal 17. Extending rearwardly from the clamping member 4 is a pair of arms 18 and 19 through the outer ends of which extends the pivot pin 20. Fixed to the pin 20 is a pair of oblong plates 21, 22, between the opposite ends of which are mounted rollers 23 of insulating material. The pivot pin 20 at the lower end thereof is bent right-angularly to form the trip member 24, which is provided near the outer end thereof with a restoring roller 25. Extending downwardly from the laterally extending portion of the arm 19 is a pair of integral lugs 26, 27, arranged to limit the backward and forward movement of the trip member 24.

The several parts just described are so arranged that when the lever 24 is in engagement with the stop member 27, the rollers 23 will engage the brushes 9 and 10, respectively, and the brushes of the set will be forced to inoperative position as shown in the upper half of Fig. 7. The controlling member will now be in such position that the pressure of the brushes on said rollers will tend to cause further clockwise rotation of the controlling member, thus preventing accidental release of the brush set. Upon slight rotation of the trip member in an anti-clockwise direction, the pressure of the brushes will force the trip member to the position shown in the lower half of Fig. 7, when the brushes will be in a position to

engage their respective stationary terminals.

Rotatably mounted in the frame member 3, parallel to the shaft 1, is a trip rod 28. This rod is provided with a plurality of 70 rearwardly extending pins 29 arranged at progressively increasing distances from the normal position of the trip members 24 carried by the brush sets. These pins are arranged in alinement and in the normal position of the rod 28, are arranged slightly at one side of the line of travel of the several trip members 24 as shown in the upper part of Fig. 7. Thus, if the brush shaft be moved upwardly until one of the trip 80 members 24 of the brush sets occupies a position in the same horizontal plane with its respective pin 29, and the rod 28 be then quickly rotated in a clockwise direction, the pin 29 will engage the trip lever 24, 85 rotating the pivot pin 20 and the parts carried thereby, thus releasing the brush set. Only one of the trip levers 24 can be engaged at a time, due to the fact that the pins 29 are arranged at progressively increasing 90 distances above the normal positions of the trip levers.

Fixed near the lower end of the rod 28 is a sleeve 30 to which is secured one end of the spring 31, the other end of this spring 95 being secured to a fixed member 32. The sleeve 30 is also provided with a pin 33 arranged to be engaged by a projection 34 on the pivoted armature of the trip magnet 36. It will thus be seen that the spring 31 tends 100 to rotate the rod 28 in an anti-clockwise direction, as shown in Fig. 7, to its normal position where it will be stopped by engagement of the pin 33 with the member 34, the outward movement of the armature 35 being limited by the engagement of its projection 37 with a fixed part of the frame. Thus it will be seen that upon energization 105 of the magnet 36 and the consequent attraction of its armature 35, extension 34 110 will engage the pin 33 on the rod 28 to rotate it in a clockwise direction, and upon deenergization of the magnet 36 the rod will be returned to its normal position by the spring 31. Means are provided for elevating the brushes at different speeds, and also for returning it by power to its normal position. These means comprise constantly rotating drive pulleys 38, 38', 38'', located in alinement on one side of an elevating bar 115 39, and electromagnetically operated idler pulleys 40, 40'; 40'' corresponding thereto, mounted in a removable frame work on the opposite side of said bar. These several driving means are substantially alike, the 120 only difference being that the up-drive power pulleys rotate at different speeds, and the down-drive pulley will rotate in the reverse direction thereto at any desired speed. 125 As these several power means are substan- 130

tially the same, only one of the devices will be described in detail and the differences of the others therefrom will be hereinafter pointed out.

Opposite the power pulley 38 and located on the other side of the elevating bar 39 but adjacent thereto, is an idler pulley 40. This idler pulley is pivotally mounted between the upwardly extending arms 41 of the bell crank lever 42. This bell crank lever in the embodiment of the invention herein disclosed is formed as a stamping from a single piece of sheet metal. Located slightly above the horizontal member of the bell crank 42 is an armature 43 of the clutch magnet 44. The armature 43 and the bell crank lever 42 are mounted on a common pivot pin 45 carried by the frame members 75 and 76. Extending upwardly from the armature 43 is a bar 46, the upper end of which is secured to one end of the spring 47. The other end of the spring 47 is attached to a bolt 48, which is adjustable in the bell crank lever 42 by means of the nut 49. The horizontal member of the bell crank 42 is held in spaced relation to the armature 43 by means of the adjusting screw 50 threaded through the armature.

Projecting outwardly from the member 46 is a finger 51 which, in the retracted position of the armature, rests upon a projection 52 integral with the frame. This prevents the armature from being removed too great a distance from the poles of the magnet 44. The down-drive and up-drive drums 38' and 38'', respectively, and their co-operating clutch mechanism are the same as that just described, with the exception that the drum, which is arbitrarily chosen as the high speed drum, will rotate substantially ten times as fast as the other. The down-drive drum 38' will rotate in the reverse direction and may be driven at any desired speed. Thus it will be seen that upon the energization of the clutch magnet 44, power will be transmitted from the armature 43 through spring 47 and bell crank lever 42 to the idler pulley 40 in order to clamp the elevating bar 39 between said idler pulley and the power pulley 38 to cause the shaft to be driven upwardly.

The application of current to the clutch magnet of the high speed drive pulley is controlled indirectly by impulses created by the interruption of the circuit extending from ground through plate 53, brush 54, conductor 55, brush 56 and interrupter 57. These impulses may be transmitted to the sending mechanism, not shown, which may act through a sequence switch relay or in any desired manner to shift the supply of current at the desired moment to the clutch magnet of the low speed pulley, or to cut it off altogether. The current to the clutch

magnet of the low speed drive mechanism will be controlled during brush selection over a similar path, with the exception that brush 58 and interrupter 59 will be substituted for the brush 56 and interrupter 57, and during units selection the interrupter 60 will take the place of interrupter 59. The several brushes shown on opposite sides of the insulating plate 61 are rigidly but insulatively secured to the yoke 62 which is fixed to the upper end of the shaft 1 in any desired manner.

In practice, the operation of the switch will preferably be as follows: The low speed clutch will be operated to cause the elevation of the brush shaft for brush selection, the amount of travel prior to the actuation of the trip rod 28 being measured by the pulsations produced by the interrupter 59. The high speed clutch will then be energized to trail the brushes of the released set over the terminals by tens, and the low speed clutch will be again energized to continue the travel by units to the desired terminal, the two latter operations being governed by the pulsations produced by the interrupters 57 and 60, respectively. When the desired terminals are reached, the upward travel of the shaft will be arrested by the de-energization of the clutch magnet, and the shaft will be held in its elevated position by the engagement of the pawl 63 with the notches or openings 64 in the elevating bar. This pawl is mounted on a pin 65 extending through the plates 75 and 76 and is held in operative position by means of the spring 65'. At its lower end it carries a pin 66 adapted to be engaged by an upward extension 67 on the armature 43' upon the energization of the down-drive clutch magnet 44'. Thus when release is desired, the electromagnet 44' will be energized, retracting the pawl 63 and simultaneously forcing the bar 39 into operative engagement with the down-drive power drum 38'. As the shaft 1 approaches its lowermost or normal position, the brush 68 will engage the segment 69. This may be used to complete a circuit for a sequence switch, relay or other device, whereby the circuit for the down-drive magnet will be interrupted. As the shaft approaches its normal position, the restoring roller 25 on the trip lever 24 will be engaged by cam member 70. This will rotate the brush-controlling member in a clockwise direction, whereby the brushes will be forced apart and separated from the stationary terminals, as shown in the upper half of Fig. 7. The brush shaft is hollow and has the circuit wires 71 inclosed therein. Branches from each of these wires are extended to the soldering terminals 17 of the corresponding brushes of the several sets on the shaft, thus connecting the corresponding brushes of all

the sets in multiple. These wires terminate in the brushes 72, which engage the conducting strips 73 terminating in the conductors 74, whereby the telephone circuits may be readily extended to the brushes and the corresponding brushes connected in multiple.

The arrangement and mounting of the several controlling magnets and parts associated therewith will now be described. All 10 of the magnets, idler pulleys, the holding pawl and the trip rod operating member are mounted in a single frame work as will presently appear and may be readily removed from the switch frame for purposes of repair or substitution by merely slightly loosening a single screw. This frame consists of the plates 75, 76, having outwardly extending arms 77, 78, 79 between which are clamped the core pieces of the magnets 36 and 44', 44 and 44'', respectively. The pivot pins for the various armatures and bell crank levers of the idler pulleys extend through these plates as clearly shown by the drawings. The plates 75 and 76 are held in spaced relation at the lower end thereof by means of the inturned portions 80 secured to the block 81 by the screws 82. Also, adjacent the lower end thereof, the plates 75 and 76 have the inturned portions 83 between which is the tapering slot 84 for a purpose which will presently appear. Each of the plates 75, 76 is provided at its upper extremity with a lug 85, which is received by an opening 86 in the lowermost frame member 3 of the switch. Fixed to the rear of the frame members 75, 76, is a spring 87 which, when the clutch magnets are in position, will engage an angle bar 88 mounted below the lowermost frame member 3 and will thus prevent vibration of the clutch structure. The bars 77 are provided with upwardly and laterally extending supporting members 89 to which is secured the member 90 having the lugs 91 and 92 between 45 which is pivotally mounted the armature 35 by means of the pin 93. The clutch frame is secured at its lower end by means of a single screw 99 passing through the tapered slot 84 and into a fixed frame member 94. 50 The bar 39 is provided at the upper end thereof with a cylindrical projection 95. This projection is retained in the lower end of the hollow shaft 1 by means of the spring catch 96, as clearly shown in Fig. 2. This 55 structure allows the bar 39 to be readily removed with the clutch magnet structure for repairs or other purposes.

In order that the attendant in searching for "trouble" may quickly and accurately 60 determine with which set of terminals of a section the switch brushes are in engagement, the elevating bar 39 is provided with a series of numerals 10, 20, 30, etc. These numerals are placed on the bar at the sides 65 of the notches or openings 64 and are posi-

tioned ten notches apart. Fixed between the plates 75 and 76 is a block 97 provided with the upwardly and inwardly projecting indicating member 98 arranged to coöperate with the numerals on the bar 39, and is so arranged that when the notch indicated by any number as 10, 20, etc., appears immediately above the indicating member 98, the brushes will be in engagement with the corresponding set of terminals in the section. The notch midway between the notches designated by numerals is indicated by a dash appearing on each side thereof. This represents the fifth terminal, that is, if the dash appearing below the notch designated as 10 in Fig. 4 were positioned immediately above the indicating member 98, the brushes would be on the fifteenth terminal. From the above it will be noted that, as shown in Fig. 4, the brushes would be positioned on the thirty-first terminal of the section. Thus in searching for trouble, the attendant by knowing which set of brushes on the shaft is tripped, and then glancing at the bar to see with which terminal of the section the brushes are in engagement, can readily tell whether the switch has fulfilled its proper function or whether the fault in the connection resides in that switch or some other switch of the series used in setting up the talking circuit.

I claim:

1. In an automatic switch, a plurality of rotatable power members located in the same plane, a bar adjacent to said power members, idler pulleys for causing engagement of said bar with said power members respectively, and electromagnets for operating said idler pulleys, said pulleys and magnets being mounted in a readily removable unitary structure.

2. In a switch, a bar, means for moving said bar in one direction, means for holding said bar against reverse movement, a rotatable power member for moving said bar in a reverse direction, an electromagnet, and means whereby the actuation of said magnet will cause engagement of said bar with said power member and will simultaneously cause said holding means to release said bar.

3. In a switch, a bar, means for moving said bar longitudinally in one direction, a pawl for preventing reverse movement of said bar, a rotatable pulley for moving said bar in the reverse direction, an electromagnet, and means whereby the actuation of said magnet will cause engagement of said bar with said pulley and will cause said pawl to be retracted.

4. In a switch, a brush shaft, an elevating bar therefor, a catch for fixing said bar to said shaft, a plurality of power members for moving said bar on one side thereof, a corresponding plurality of coöoperating idler pulleys on the other side of said bar, operating

- magnets for said idler pulleys, a frame for supporting said pulleys and magnets, and means whereby said frame and elevating bar may be readily removed from said switch 5 in a unitary structure.
5. In an automatic switch, a brush shaft, opposed pairs of brushes upon said shaft, a controlling device between the innermost brushes of said pairs, said device being rotatable in a plane at right angles to said shaft, and means for engaging said controlling device to release said brushes during the initial movement of said shaft.
10. In an automatic switch, a pair of opposed brushes, a controlling device for said brushes rotatable in the plane therewith, said controlling device being so arranged that in one position it will engage the adjacent sides of said brushes, whereby said brushes will be rendered inoperative and when in another position said brushes will be allowed to become operative.
15. In an automatic switch, a brush support, a set of opposed pairs of brushes in substantially the same plane on said support, a brush controlling device normally holding said pairs of brushes separated to inoperative position, said device being positioned between the innermost 20 brushes of said pairs and rotatable in the plane thereof, a brush tripping device, and means for momentarily rotating said tripping device during the preliminary movement of said support to release said sets of 25 brushes.
25. In a switch, stationary contacts, a pair of brushes for engagement therewith, a rotatable pin between said brushes extending at right angles to the plane thereof, a brush controlling device on said pin, and means for rotating said device to govern the engagement of said brushes with said contacts.
30. In a switch, a row of terminal sets, a set of brushes, a support therefor, means for moving said support to cause said brushes to traverse said row, a device rotatable in a 35 plane transverse to the line of travel of said brushes carried by said support, and means for rotating said device to determine the operative or inoperative condition of said 40 brushes.
35. In a switch, rows of terminals, a pair of brushes, a support therefor, means for moving said support to cause said brushes to traverse said terminals, a device carried by said support between said brushes and rotatable in a plane transverse to the line of travel thereof, and means for rotating said device to determine the operative or inoperative condition of said brushes. 45
40. In a switch, rows of stationary terminals, a pair of normally retracted brushes, a support therefor, means for moving said support to cause said brushes to traverse said rows, a device carried by said support between said brushes and rotatable in a plane transverse to the line of travel thereof, a rod, a projection thereon, and means for rotating said rod, whereby said projection will engage said device to release said brushes. 50
45. In a switch, rows of terminal sets, a support, brushes carried thereby, a bar secured to said support, power means for engaging said bar to move said brushes over said terminal sets, and means associated with said bar for indicating with which terminal set said brushes are in engagement. 55
50. In a switch, a row of terminal sets, a support, brushes carried thereby, a bar secured to said support, power means for engaging said bar to move said brushes over said terminal sets, said bar being provided with a series of numerals for indicating with which terminal set said brushes are in engagement. 60
55. In a switch, a row of terminal sets, a support, brushes carried thereby, a bar secured to said support, power means for engaging said bar to move said brushes over said terminal sets, said bar being provided with a series of numerals for indicating with which terminal set said brushes are in engagement. 65
60. In a switch, a row of terminal sets, a support, brushes carried thereby, a bar secured to said support, power means for engaging said bar to move said brushes over said terminal sets, said bar being provided with a series of numerals for indicating with which terminal set said brushes are in engagement. 70
65. In a switch, a row of terminal sets, a support, brushes carried thereby, a bar secured to said support, power means for engaging said bar to move said brushes over said terminal sets, said bar being provided with a series of numerals for indicating with which terminal set said brushes are in engagement. 75
70. In a switch, a row of terminal sets, a support, brushes carried thereby, a bar secured to said support, power means for engaging said bar to move said brushes over said terminal sets, said bar being provided with a series of numerals for indicating with which terminal set said brushes are in engagement. 80
75. In a switch, a row of terminal sets, a support, brushes carried thereby, a bar secured to said support, power means for engaging said bar to move said brushes over said terminal sets, said bar being provided with a series of numerals for indicating with which terminal set said brushes are in engagement. 85
80. In witness whereof, I hereunto subscribe my name this 19th day of November A. D., 1913.
